CLAIM

The ornamental design for a telephone set with transparent outer surface and neon-light tube surrounding the base as shown and described.

DESCRIPTION

FIG. 1 is a left side, top and front perspective view of a telephone set with transparent outer surface and neon-light tube surrounding the base showing my new design in cradled relationship;

FIGS. 2 and 3 are respectively left and right side elevational views thereof;

FIGS. 4 and 5 are respectively rear and front elevational views thereof; and

FIGS. 6 and 7 are respectively top and bottom plan views thereof.

FIG. 1.

FIG. 2.

FIG. 3.

FIG. 4.

FIG. 5.
